[57] **CLAIM**

The ornamental design for an upper part of track tongue for a handpowered palett truck, as shown and described.

DESCRIPTION

FIG. 1 is a front perspective view of an upper part of a track tongue for a handpowered palett truck showing my new design;

FIG. 2 is a front elevational view thereof;

FIG. 3 is a top plan view thereof;

FIG. 4 is a side elevational view thereof; and,

FIG. 5 is a bottom plan view thereof.

All views are shown broken away for ease of illustration.
